(57) **CLAIM**

The ornamental design for a tubing bender, as shown and described.

DESCRIPTION

FIG. 1 is isometric view depicting a tubing bender, according to a first embodiment of the disclosure.

FIG. 2 is a right-side view of the tubing bender of FIG. 1.

FIG. 3 is a left-side view of the tubing bender of FIG. 1.

FIG. 4 is a rear view of the tubing bender of FIG. 1.

FIG. 5 is a front view of the tubing bender of FIG. 1.

FIG. 6 is a top view of the tubing bender of FIG. 1; and,

FIG. 7 is a bottom view of the tubing bender of FIG. 1.

In each of the figures, portions or features of the tubing bender shown in broken lines form no part of the claimed design.

1 Claim, 4 Drawing Sheets
